UNITED STATES PATENT OFFICE.

ALFRED FRESCHL, OF OSHKOSH, WISCONSIN.

TUFTING.

SPECIFICATION forming part of Letters Patent No. 537,385, dated April 9, 1895.

Application filed April 26, 1894. Serial No. 509,165. (No model.)

To all whom it may concern:

Be it known that I, ALFRED FRESCHL, a citizen of the United States, residing at Oshkosh, in the county of Winnebago and State 5 of Wisconsin, have invented certain new and useful Improvements in the Manufacture of Tufting; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 My invention relates to an improved method and means of making tufting for use in upholstering, and to the article produced thereby, and the objects of my invention are to simplify and cheapen the cost of manufacture, secure flexibility, and increased convenience in its application to furniture, &c., and at the same time have it possess beauty and uniformity of appearance, while it is sufficiently durable for the purposes for which it 20 is intended; and it consists in a novel method and product, as will be hereinafter described and claimed.

In the accompanying drawings, Figure 1 is a plan view of my improved tufting when 30 completed. Fig. 2 is a sectional view through the same; and Fig. 3 is a perspective view of the mold and the tufting in the process of manufacture. In this view the forming block is shown as it appears before being pressed 35 down into a cell of the mold, against the ornamental fabric, and also as it appears after having been pressed down into a cell, against the fabric.

Similar letters refer to similar parts in each 40 view.

In the drawings, A represents a suitable base which is formed with grooves a, corresponding to the shape of the mold or former B which is placed in the same, and C represents a forming block. The former or mold B, may be of any desired shape and depth, and is constructed of metallic strips, which are set edgewise in the grooves in the base A, as shown.

50 In my method of manufacturing tufting, I first spread the fabric or material forming the outer surface of the tufting, with its finished

ornamental face downward upon the mold, and arrange different portions of it, progressively or successively, within the cells or chambers of the mold as follows: Fabric material enough to form one tuft is pressed into a cell or chamber, either by a block C, or by the hand; and this formed tuft, if produced by hand without the aid of the block C, is secured by inserting into it the requisite amount of stuffing material, and confining this material by means of a piece of card board of an area and form corresponding about to that of the cell. In the drawings the card board is 55 lettered M, and this card board is inserted by hand pressure against the filling, into the cell, so as to lie with its full thickness below the edges of the partitions which inclose the cells of the mold, and frictionally bind against the 60 partitions of the cell. If the block C is used, it is pressed down and then raised out of the cell and the filling or stuffing is inserted and confined by a piece of card board M. It is preferable to thus completely arrange each 65 tuft before a succeeding tuft is commenced, as, by this means, any chance for a portion of the quantity of material required for one tuft, being drawn out of the cell, is prevented, and no portion of the material used in forming 70 a preceding tuft, will be used in forming a succeeding tuft, and thus uniformity of 75 shape and depth of the respective tufts is insured. All of the tufts are formed successively, or progressively, in the same manner 80 as the one first formed. When all the tufts have been stuffed and each has had a piece 85 of card board pressed down upon its stuffing or filling material, flush with the upper edges of each cell, a narrow space, equal to the 90 thickness of the partitions of the mold, remains between each of the tufts, on all sides, or all around, and a chance for the ornamental fabric to come in contact with the top edges of the partitions of the mold, is afforded, 95 and thus a flexible connection is secured between each tuft when the product is finished, and at the same time a supporting foundation for the filling for each tuft is also secured. The several foundation pieces are kept in 100 place by means of a flexible backing E formed of canvas or other material, and glued or cemented or otherwise suitably secured to the surface of the tufted fabric at the points

where the tufting material comes in contact with the top edges of the partitions of the mold or former. The backing E is attached at its outer edges directly to the surface material, where it turns over the edges of the mold. The glue or cement may be so spread as to also cover the card board pieces, and thus the backing be glued to them as well as to the ornamental fabric. After the glue is dry the fabric is removed from the mold, and may be finished with buttons N, N, if desired, for ornamentation.

The separated card board pieces M constitute an essential feature of my invention, as they enable me to produce tufting of the most perfect character out of fine as well as coarse materials. It is very important to employ the separate pieces of card board for retaining the filling in each of the respective tufts until all the tufts are formed. Furthermore, by their use flexibility is secured, and facilities are afforded for gluing or cementing the tufted fabric to the canvas or other backing sheet, a result that has not heretofore been effected with plaited tufted fabrics. A continuous piece of card board has been employed as a foundation, and under such construction the gluing or cementing of the tufted fabric to this card board would have interfered with the formation of the plaits, and this being so, the tufts in such plaited fabrics are not held in position independently, and a flexible connection between each of the tufts, all around, is not secured, and consequently the tufting known as "plaited tufting," as an article of trade and use, is stiff and cannot be applied conveniently, uniformly, and artistically around curved or uneven surfaces. All of these inconveniences are avoided by my invention, and the same

are specially effected by the improved method employing the separated pieces of card board or other analogous material in conjunction with a mold, filling or stuffing substance, ornamental fabric, cementing material and a canvas backing, in the manufacture of tufted fabric as hereinbefore described. 45

What I claim as my invention is—

1. The improved method of making hand made tufting for upholstery, which consists in laying a piece of pliable material face downward, loosely, over a form having a plurality of depressed molds, pressing the material into said molds, filling the depressions formed in the material with a suitable pliable substance, inclosing or covering the filled depressions with separated pieces of card-board or analogous material, and finally applying and permanently securing a backing of cloth or other suitable pliable material over the back of the entire article, substantially as described. 55

2. As an improved article of manufacture, to wit, tufting, which comprises in its construction, an outer ornamental piece of material provided with spaced tufts having a flexible connection between them, and the tufts filled with a suitable yielding material, separate pieces of card-board or equivalent material for holding the filling material in each tuft, in place, and a backing of cloth or suitable pliable material applied over the back of the entire article and permanently secured thereto, substantially as described. 60

In testimony whereof I affix my signature in presence of two witnesses. 75

ALFRED FRESCHL.
